UNITED STATES PATENT OFFICE.

GEORGE H. TOZIER, OF ROCHESTER, NEW YORK, ASSIGNOR TO EASTMAN KODAK COMPANY, OF ROCHESTER, NEW YORK, A CORPORATION OF NEW YORK.

CARBOY BOX.

Application filed November 9, 1923. Serial No. 673,805.

To all whom it may concern:

Be it known that I, GEORGE H. TOZIER, a citizen of the United States of America, residing at Rochester, in the county of Monroe 5 and State of New York, have invented certain new and useful Improvements in Carboy Boxes, of which the following is a full, clear, and exact specification.

This invention relates to containers, and 10 particularly to containers for carboys. One object is to provide a carboy box having means for cushioning horizontal and vertical blows, such as are customarily received in shipping such articles. Another object is to 15 provide a frame which closely embraces the carboy. Another object is to provide the cushioning means between the carboy holding frame and the box. Another object is to provide a box which may be used with 20 different sized crates for shipping different sized carboys. Other objects will appear hereinafter in the specification, the novel features being pointed out in the claims at the end thereof.

25 In the drawings:

Fig. 1 is a section on line 1—1 Fig. 2 showing a carboy in a shipping box constructed in accordance with and illustrating one form of my invention;

30 Fig. 2 is a plan view of the carboy and box shown in Fig. 1;

Fig. 3 is a side elevation of the carboy holding frame;

Fig. 4 is an enlarged section of a spring 35 holding block, taken on line 4—4 of Fig. 3;

Fig. 5 is a perspective view of the box with the carboy frame removed; and

Fig. 6 is an enlarged section on line 6—6 40 of Fig. 4, showing a bottom plan of the spring holding block.

This container was particularly designed for holding large carboys of acid where great care must be taken against breakage in shipping. The bottle 1 may be of glass of 45 the well known type having substantially straight sides 2, a concave bottom 3, neck 4, and a stopper 5.

This carboy is carried by a frame 6, best 50 shown in Figs. 3 and 4, consisting of a plurality of frame members 7 each of which may have an inner longitudinal concavity at 8 to closely fit the sides 2 of the carboy 1. These frame members are supported by bottom members 9 fastened together at the 55 center 10 (Fig. 1). It will thus be seen that

the carboy 1 is supported at a plurality of points 11 upon the bottom members 9 where these members contact in a horizontal plane with the bottom and the sides 2 are supported throughout a substantial part of the height of the bottle by the side supporting members 7, where these members contact with the sides over extended vertical areas. For each size of carboy there is preferably a corresponding suitable frame 6, although, as 60 will be hereinafter described, one frame will readily care for material variations in size and shape of carboys, such as may occur in manufacture.

Each of the side supporting members 7 70 carries on each end a spring holding block 12, fastened in any preferred way. Each block, see Figs. 4 and 6, has a wedge shaped groove 13 cut therein so as to form holders for the ends 14 of the spring members 15. 75 The springs are preferably of suitable stout wood, such as selected ash. Each groove 13 is such a size and shape that the ends 14 do not slide in the groove 13 when the spring member is compressed. As shown in dashed 80 lines in Fig. 3, when pressure is applied at 16 the center portion of the spring flattens out. This structure forms a strong resilient spring which will absorb the shocks between the box and the carboy.

Like the side supporting member 7, each bottom supporting member 9, also carries a spring holding block 22. These blocks are just like blocks 12 in structure. The ends 24 of spring members 25, also preferably 90 of wood, are confined in grooves 23, and the center portions 26 of the spring members cross beneath the center of the carboy.

Since the carboy side supporting members 7 are resiliently mounted they will automatically care for different sized carboys within certain limits; beyond which supplementary frames 6 of different size must be provided. It is, however, usually preferable to vary the size of the box in proportion.

The bottom spring members 25 rest upon the bottom 30 of box 31, and the side spring members slide into grooves 32, preferably made by fastening strips 33 on the triangular corner boards 34. This construction allows either the carboy and frame to be loaded into the box, or the carboy to be loaded into the assembled frame and box as may be desired.

The corner boards 34 support the sides 110

37 of the box, and handles 38 in the form of cleats may be attached to the sides as shown in Figs. 1 and 2, if desired.

It should be noted that as the springs have 5 a very small portion contacting with the box, that the inner frame is supported in a form of cradle to which few shocks are transmitted through the springs. In the form shown there are only five points of contact between 10 the inner frame and box.

While I have illustrated in the drawings a preferred form of my invention, I do not wish to be limited to this form, and contemplate as within the scope of my invention 15 all such modifications and equivalents as may come within the scope of the following claims.

Having thus described my invention, what I claim as new and desire to secure by 20 Letters Patent is:

1. In a carboy container, the combination with an inner frame adapted to engage the sides of a carboy, of a box, spring members between the frame and box, said spring 25 members being attached to one of the above named parts and having a slideable connection with the other part.

2. In a carboy container, the combination with an inner member adapted to engage a 30 plurality of faces of a carboy, of a box adapted to receive the inner member, springs for supporting the inner member in the box, the springs being attached to the inner member.

3. In a carboy container, the combination with an inner member adapted to engage a 35 plurality of faces of a carboy, of a box adapted to receive the inner member, springs for supporting the inner member in the box, the springs being attached to the inner

member and forming runners upon which the inner member may be slid to and from the box.

4. In a container, the combination with an inner member adapted to engage a face of a carboy, a spring member carried by the inner member, a box to contain the inner member, a slideway in the box, the inner member being spaced from the box by the spring which may slide in the slideway in 50 the box.

5. In a container, the combination with an inner member adapted to engage a face of a carboy, spring holding blocks at the 55 ends of the inner member, a spring member held by the blocks and bowed outwardly between the blocks, a box adapted to receive the inner member and spring, said bowed springs engaging a portion of the box.

6. In a container, the combination with an inner member adapted to engage a face of a carboy, spring holding blocks at the ends of the inner member, a spring member held by the blocks and bowed outwardly between the blocks, a box adapted to receive the inner member and spring, a corner of the box having a grooved corner member in which the bowed spring may slide to space the inner member from the box.

7. In a container, the combination with a frame for engaging the side and bottom walls of a carboy, of a box adapted to receive the inner frame and carboy, of springs supporting the inner frame spaced from the box, said springs being bowed and having the bowed portion contacting with the box.

Signed at Rochester, New York, this 31st day of October, 1923.

GEORGE H. TOZIER.
